Specification for Design.

Patented Oct. 30, 1917.

Application filed July 31, 1917. Serial No. 183,780. Term of patent 7 years.

To all whom it may concern:

Be it known that I, EUGENE C. BAECK, a citizen of the United States, and a resident of Irvington-on-the-Hudson, in the county of Westchester and State of New York, have invented a new, original, and ornamental Design for a Wall-Covering, of which the following is a specification, reference being had to the accompanying drawing, forming part thereof.

The figure is a face view of a portion of a wall covering showing my new design.

I claim:

The ornamental design for a wall covering as shown.

EUGENE C. BAECK.
